KENNETH M. GIVEN, OF BRONXVILLE, NEW YORK, ASSIGNOR TO A. KIMBALL COMPANY,⁵⁰
OF NEW YORK, N. Y., A CORPORATION OF NEW YORK

STRING-KNOTTING APPARATUS

Application filed March 26, 1929, Serial No. 350,004. Renewed May 9, 1931.

My invention relates to improvements in apparatus or machines for use in knotting twine, thread, or string, or in attaching same to tags, labels, and other articles.

5 One object of my invention is to provide an improved machine whereby a label or other article may be provided with a string which is thereafter knotted so as to provide a permanent attachment. A further object 10 of this invention is to provide an improved apparatus whereby labels, tags, or the like may be attached to articles of merchandise by means of knotted string. A still further object of the invention is to provide an improved machine comprising means whereby a string is passed through a label or the like and through an article of merchandise and is thereafter knotted so as to retain the label or the like permanently attached to the said 15 article. A still further object of this invention is to provide improved means whereby a string is provided with two depending ends, and means whereby such ends are knotted together. A still further object is to provide 20 improved means whereby a string is looped through or around one or more articles and is then manipulated to form a knot in close proximity to the article or articles through or around which the string is looped.

25 With these objects in view the invention consists in the novel construction and arrangement of parts hereinafter described, illustrated in the accompanying drawings, and particularly pointed out in the appended 30 claims, it being understood that various changes in the arrangement and constructional details may be made without departing from the spirit or sacrificing any of the advantages of the invention.

35 In the drawings, Fig. 1 is a side view of the machine with parts thereof in vertical section;

40 Fig. 2 is a detail plan view showing a part of the string guiding means;

45 Fig. 3 is a front view shown partly in section on the line 3—3 of Fig. 1;

50 Figs. 4 to 12 inclusive are detail front views showing, in nine different positions, part of the mechanism for forming the string into a loop with two depending ends;

Fig. 13 is an enlarged detail front view showing part of the mechanism for knotting the string;

Fig. 14 is a side view looking on the right-hand side of Fig. 13;

Fig. 15 is a vertical section taken on the line 15—15 of Fig. 14;

Fig. 16 is an enlarged detail view, shown partly in section, of the rotary head and reciprocating core of the knot-tying mechanism;

Fig. 17 is a vertical section of the same parts, partly in outside view, showing a different position of the core;

Fig. 18 is a plan view with the cover removed from the rotary head, and with the core in cross-section;

Figs. 19 and 20 are plan views of the same parts, showing two different stages in the operation;

Figs. 21, 22 and 23 are similar views showing three further stages in the operation and also show the cooperating members for use in forming the knot;

Fig. 24 is an enlarged side view of the upper part of a rotary head with an attachment for use in tightening the knot;

Fig. 25 is a plan view of the same; and

Figs. 26 and 27 are views corresponding to Fig. 24, but showing successive stages in the operation of the knot-tightening device.

The machine is built with a base 30, front and rear frames 31, 32, side frames 33, 34, and a top or table 35 supported upon said frames and having a thin upper covering plate 36. The table 35 is made with an opening 37 and above such opening the covering plate 36 has a hole 38 for the passage of a vertically reciprocating needle 39 depending from a bracket 40, secured to a slide rod 41, which latter is splined in a bearing 42 carried by a bracket 43 mounted upon the table 35, and in a bearing 44 depending from the under side of the table. The lower end of the slide rod 41 is slotted for engagement by the outer end of the lever arm 45 by means of which the slide rod is reciprocated so as to raise and lower the needle 39; the arm 45 being fulcrumed in a bracket 46 mounted upon the side frame 33, and integral with this arm 45 is a

short arm 47 carrying a roller 48 which engages a cam groove 49 in a cam wheel 50 keyed to the main shaft 51 of the machine.

Mounted in the opening 37 in the table 35 is a bracket 53 (see Fig. 2) having a tapered slot 53 with its wide portion or mouth in line with the opening 38 for the needle, and mounted on the under side of the table 35 is a cradle 54 which supports a rotary head 55 with a vertical bore 56 therein, normally located directly in the path of the needle 39. A downwardly tapered opening 57 in the bottom of the cradle 54 (see Fig. 1) is also arranged in the path of the needle so that the latter may pass through the rotary head and depend beneath the cradle in the position indicated in dotted lines at Figs. 1 and 3. Secured in the lower part of the rotary head 55 is a depending hollow shaft 58 (see Fig. 17) which passes through an opening in the under part of the cradle 54 and is mounted at its lower end in a bearing 59 projecting from a frame 60 hereinafter referred to.

Referring particularly to Figs. 13 to 15, the hollow shaft 58 is provided on its lower end with a bevel pinion 61 which meshes with and is driven from a bevel wheel 62 keyed on a short shaft 63 adapted to be driven by means of a slotted star gear 64 thereon. The frame 60 hereinbefore referred to is mounted on the base 30 and is provided with bearings for the said shaft 63 and also for the main shaft 51 which latter carries a disc 65 having a roller 66 adapted to engage the slots of the gear 64 so as to rotate the shaft 63 and the bevel wheel 62 through one-quarter of a revolution to each complete revolution of the main shaft 51, and the gear ratio of the bevel gear 61, 62 is such that one complete revolution is imparted to the bevel pinion 61 and thus to the rotary head 55 during each complete revolution of the main shaft 51; but the gears are so timed that the rotary head 55 makes one complete revolution and remains stationary during the remainder of the cycle of operations.

Extending forwardly from the frame 60 are two brackets 67, 68 having vertical openings 69 to serve as guides for a rod 70 mounted within the hollow shaft 58 for the purpose hereinafter described. Mounted on the front of the brackets 67, 68 is a slotted plate 71 and extending through the slot is a stud 72 confined between two collars 73 secured on the shaft 70, and mounted on the outer extremity of the stud 72 is a roller 74 which engages a cam groove in a wheel 75 secured on the main shaft 51 and the formation of this cam groove is such that one upward and downward movement is imparted to the shaft 70 during each complete revolution of the main shaft 51. At its upper end the said shaft 70 is secured (see Figs. 16 and 17) to a reciprocating core 76 which is thus raised

and lowered in the manner required and as hereinafter more fully set forth.

The frame 60 also carries a shaft 77 which supports a boss 78 having a hook member 79 adapted to pass between the front of the needle 39, and the string in the eye thereof. As the needle commences its upward movement and the string is retarded at the front of the needle by engagement with the lower extremity of the tapered opening 57 the hook member 79 is swung into the string-engaging position by means of an arm 80 extending from the boss 78 and having a roller engaging a suitably shaped cam groove in a cam wheel 81. Also mounted on the shaft 77 is a boss 82 having an arm 83 adapted to hold the string against the side face of a depending part 84 on the cradle 54 and another boss 85 carries a knife 86 adapted to engage the rear face of the said depending part 84 with a shearing action and to sever the string, the boss 85 being operated by an arm 87 having a roller engaging a cam groove in a wheel 88, while the boss 82 is actuated by means of a spring 89 in compression between the bosses 82 and 85 in such manner that the operation of the arm 87 first causes the arm 83 to engage the part 84 in front of the knife 86 and further movement of the arm 87 brings the knife 86 into operation while the compression of the spring 89 due to the relative movement of the bosses 82, 85 increases the pressure of the arm 83 upon the depending part 84. The shaft 77 also carries a boss 90 having an arm 91 adapted to engage a recess 93 in the part 84 to anchor the string during one part of the operation and an aperture 94 in the arm 91 is located in the path of the needle while the string is being so anchored for the purpose hereinafter described. For the operation of the arm 91 the boss 90 has an arm 95 with a suitable roller engaging a properly shaped cam groove in a cam wheel 96.

The rotary head 55 and the reciprocating core 76 operate to form the knot in the string, the rotary head being rotated by means of the hollow shaft 58 (see Fig. 17) in the manner hereinbefore described through the medium of the bevel gear 61, 62 and the parts 64, 65, 66; and reciprocating motion is imparted to the core 76 by the inner shaft 70 through the medium of the roller 74 and the cam wheel 75, all as hereinbefore described. Referring particularly to Figs. 16, 17 and 18, the head 55 is recessed to accommodate the core 76 in the upper part thereof, and the vertical hole 56 hereinbefore referred to permits free passage of the needle 39 when the head 55 is in its normal position. The front of the core 76 is formed with a central vertical groove 97 to accommodate a cam or inclined projection 99 and a pair of guide strips or plates 99' formed in the interior of the head; and at the back of the core a vertical groove 98 is provided to facilitate disen-

gagement of the loop of string from the core and for the accommodation of a hook 117 hereinafter described. Near the upper end thereof the core 76 is formed with a central opening 100 through which the ends or other parts of the string may be introduced by means of a member 101 as hereinafter described, and just below this opening 100 the vertical front edges of the core are provided with ridges 102 for pulling the string beneath the path of the member 101. The head 55 is provided with a removable cover 103 and below this cover the head is formed with a recess 104 for the admission of the member 101 and with a rear recess 105 for the accommodation of a pair of spring blocks 106 which are pressed against each other by means of the springs 107 and are adapted to retain the ends or other parts of the string introduced by the member 101, which latter is forked to engage above and below the said blocks and is grooved at its extreme end 108 to guide the string between the engaging faces of the blocks 106. The cover 103 of the head 55 is formed with an arc-shaped slot 109 for the reception of a swinging member 110 (see Figs. 21 to 23) having a forked end 111 adapted to engage the string passed round the upper part of the core and to move same to one side to ensure engagement of the string by the said ridges 102 during their downward movement in the manner hereinafter more fully set forth. Below the cover 103 the head 55 is recessed for the reception of a sliding gate piece 112 (see Figs. 16 and 18) for retaining the string in position in the hole 56. This gate piece 112 is provided with a spring 113 by means of which it is normally held in its operative position, but a lower projecting part 114 thereon is beveled for engagement with the end of a rod or bracket 114' carried on the member 101 and adapted to enter a guide opening provided therefor on the head 55. The member 101 and the part 114' are so arranged that the introduction of the said part 114' presses the parts 112, 114 to one side against the action of the spring 113, so as to release the string in the manner required as the end 108 of the member 101 passes through the opening 100. At the lower extremity of the hole 56 in the head 55 a loose ring or bushing 115 is mounted and a spring 116 normally presses the ring 115 into contact with the upper surface of the cradle 54 so as to exert the desired pressure on the string during the rotation of the head 55.

One purpose of the groove 98 in the back of the core 76 is to accommodate the said hook device 117 (see Figs. 24 to 27) for moving the loosely formed knot upwardly toward the article through or around which the string has first been threaded. Cooperating with this hook 117 is a fork 118 which disengages the loop of string from the hook

117 and presses and tightens the knot in an upward direction. Pivotaly mounted on the side of the head 55 are a pair of arms 119 having a cross-bar 120 upon which the hook member 117 is pivoted. The arms 119 also carry a cross bar 121 upon which the fork member 118 is pressed by the action of a spring 122. The hook 117 and the fork 118 are both pivotally supported by a pair of arms 123 mounted on a cross bar 124 which is carried in brackets 125 on the back of the rotary head 55 and has an operating shoe 126 adapted to be engaged at the proper time by a plunger 127 slidably mounted in a projection 128 on the cradle 54 and in a bracket 129 on the frame 60. The lower end of the plunger 127 has a roller 130 for engagement with the periphery of a cam 131 and a spring 132 is held in compression between the under side of the projection 128 and a collar 133 on the plunger, so that the roller 130 is retained in engagement with the periphery of its cam and the lower part of the plunger 127 is squared or splined to prevent rotation thereof in the bracket 129.

In the operation of forming the knot the cooperating members 101, 110 (see Figs. 1 and Figs. 21, 22, 23) are operated in proper sequence and at the correct time by a double armed lever 134, 135 mounted on a bracket 136 on the front frame 31 of the machine. The lower extremity of the arm 135 is provided with a roller 137 which is engaged and operated by a peripheral cam groove 138 in a drum 139 fast on the main shaft 51, and the upper extremity of the arm 134 engages a slot 140 in the front end of the reciprocating member 101 which is supported by means of a pair of brackets 141, 142 on the under side of the table 35, while the swinging member 110 is supported by means of a pivot 143 on the under side of the said table. A pin 144 on the member 101 engages a slot 145 in the member 110 and this slot is so shaped that the movement of the member 101 from the position shown at Fig. 21 to that shown at Fig. 22 swings the member 110 into the operative position and further movement of the member 101 causes it to function and to bring the string into engagement with the retaining blocks 106 (see Figs. 17, 18 and 23), and during this latter movement—or part of the movement—of the member 101, the swinging member 110 is free to move back from the position shown at Figs. 22 and 23 when the pull on the string is sufficient to cause such a movement; the slot 145 being so shaped at 145' that backward movement of the member 110 is permitted. Retraction of the member 101 due to the contour of the cam groove 138 first withdraws the member 101 from its operative position and then causes the withdrawal of the member 110, all for the purpose hereinafter more fully set forth.

- 5 The needle 39 employed in this machine is of any suitable or well-known construction, and is formed in the rear side thereof with a longitudinal slot 39' for the accommodation of the string (see Fig. 1) while the front side of the needle is formed with only a short groove 39'' which accommodates only a very short length of the string, with the result that the ledge forming the lower extremity of the 10 hole 57 in the cradle 54 retards the upward movement of the string during the upstroke of the needle, so that a loop is formed for the reception of the hook member 79 in front of the needle.
- 15 15 The machine is driven by an electric motor 146 mounted on the base 30 of the machine and the drive is transmitted by a pinion 147 mounted on the motor shaft 148 which is supported by a bracket 149, and a 20 spur wheel 150 loose on the main shaft 51 is in constant mesh and is driven by the pinion 147. For transmitting the motion of the spur wheel 150 to the main shaft 51 a sliding clutch member 151 is splined on the shaft 51 and has a friction ring 152 adapted to engage a similar ring 153 secured to the spur wheel 150, and has another friction ring 154 adapted to engage a similar ring 155 secured to a bushing 156 anchored to the rear frame 32 of the machine. A yoke 157 pivotally mounted in a bracket 158 on the said frame 32 is swung by means of an arm 159, while a slide rod 160 mounted in guides 161, 162 is adapted to be moved backwardly by means 30 of a knob 163 to swing the yoke 157 and cause engagement of the clutch. The control rod 160 is normally retained in its forward position by means of a spring 164 in compression between the guide 161 and the knob 163.
- 35 40 For retaining the clutch device in the engaged position a latching device 165 is provided, this device being mounted with a universal joint 166 in a fixed bracket 167 depending from the said bracket 158, and a 45 spring 168 holds the latch device 165 in engagement with a depending central lug 169 on the yoke 157. In the position shown at Fig. 1 the mechanism is in position for the commencement of a cycle of operations, and 50 backward movement of the control knob 163 throws the clutch into engagement and commences the operation. When the main shaft 51 has made one complete revolution, however, a projection 170 on the clutch 151 engages the latching device 165 and swings the 55 same in a lateral or sidewise direction out of engagement with the central lug 169 so that the yoke 157 is free to swing under the action of the spring 164 on the control rod 160 until the parts assume the position illustrated at Fig. 1, the mechanism being instantly brought to rest in readiness for the commencement of the next cycle of operations.
- 60 65 A string-supply spool 171 is mounted on

the table 35 at the back of the machine and the string 172 from this spool is led through a guide 173 on the bearing 42 and through a tension device 174 on the bracket 40 and through a guide 174' to the needle groove 39' 70 and thence to the eye of the needle 39.

The construction of the various parts of the apparatus will be clearly understood from the foregoing description, but in order that the operation of the machine may be more 75 clearly and more readily understood, I will now describe the complete cycle of operations.

At the commencement of the operation the parts of the machine are in the position indicated at Fig. 1 and power is supplied to the 80 electric motor 146 in order to continuously rotate the spur wheel 150 on the main shaft 51. The operator stationed in front of the machine places the labels, tags, or other articles in the proper position beneath the 85 needle 39 and, in order to commence the operation of the machine, the operator presses back the knob 163 thereby throwing the clutch 151 and causing the main shaft 51 to rotate with the spur wheel 150. 90

The rotation of the shaft 51 carrying the cam wheel 50 reciprocates the slide rod 41 thereby causing the needle 39 with the string 172 threaded through the eye thereof to descend through the hole 38, slot 53, bore 56, and hole 57 to the position indicated in dotted lines at Fig. 1, and as rotation of the cam wheel 50 is continued the cam 49 reverses the movement of the needle and the part of the string in front of the lower part of the needle 95 is retarded by the lower extremity of the hole 57, so that a loop is formed in front of the needle, and as the needle 39 continues to rise the cam wheel 81 operates the hook member 79 which is swung into the position indicated at Fig. 4 where the arrow indicates the direction of movement of the needle, and the hook 79 is shown in engagement with the string. As the operation continues the cam wheel 88 swings the holding member 83 into the position indicated at Fig. 5, so as to retain the end of the string and further movement causes compression of the spring 89 and operation of the knife 86 into the position indicated at Fig. 7 where the end of the string 100 is cut off, but, before the string is cut by the knife 86, the cam wheel 96 swings the arm 91 so as to hold the string against the recess 93 (see Fig. 6). As the needle again descends as shown at Fig. 8 the hook 79, 110 holder 83, and knife 86, are swung back into the inoperative position by their cam wheels 81, 88. In this second downward movement the needle passes through the aperture 94 in the arm 91, as shown at Fig. 9, and as the needle rises for the second time the hook member 79 again comes into operation (see Fig. 9) and as this upward movement continues the holding device 83 is brought into operation (see Fig. 10) and the knife 86 sub- 120 125 130

sequently severs the string (see Fig. 11), in the manner hereinbefore described; and after the needle has been raised clear of the rotary head 55 the cam wheels 81, 88, 96 then with-
 5 draw the hook 79, holder 83, knife 86 and arm 91 into the position indicated at Fig. 12 thereby releasing the depending ends of the string; and for the remainder of this cycle of operations the needle 89 is held in its
 10 raised position and the parts 79, 83, 86, 91 remain inactive in readiness for the commencement of the next cycle; the cam groove 49 being so shaped that the four-stroke cycle of the needle takes place and the needle then
 15 remains stationary in its initial position as shown at Fig. 3 where the cam wheel 50 rotates in the direction of the arrow.

It will be understood that the label, tag, or other article 176, (Figs. 4 to 12) is manipulated by the operator so that the needle in one of its downward movements passes through the label or other article (or through the eye thereof) and in the other downward movement of the needle the label or other article is moved so that the needle passes clear of the label (see Fig. 8) or through a different portion thereof.

Figs. 4 to 12 show by way of example a label 176 having the string 172 threaded therethrough, but it will be readily understood that the needle may be conveniently caused to penetrate a label or the like and also to penetrate the article to which the label is to be attached so as to form a loop threaded through the label or other article and having the free end passing downwardly through the bore 56 in the rotary head 55, or the string may be passed around one or more articles or may be otherwise attached thereto.

40. After the completion of the operation of the needle as above described the continued operations of the shaft 51 brings the cam wheel 75 into position for its cam groove to raise the roller 74 and thus raise the core 45. 76 within the head 55, so that the said core is brought into the position shown at Fig. 16, and while the cam groove in the cam 75 retains the core 76 in its raised position the head 55 is caused to make one complete revolution in a counter-clockwise direction (see Fig. 20), this rotary movement being imparted to the head 55 by the action of the roller 66 which at the proper time engages one of the radial slots in the slotted wheel 64 and rotates the latter through one-quarter of the revolution, and as similar movement is imparted to the bevel wheel 62 the bevel pinion 61 is caused to make a complete revolution and the head 55 rotates therewith.

60. As the head 55 rotates yielding pressure is exerted by the ring 115 upon the free ends of the string, so that the necessary tension is provided in the string between the ring 115 and label, tag or other article engaged by the string.

Fig. 19 is a plan view showing the head after the completion of the first two strokes of the needle, and Fig. 20 is a similar view after the completion of the four strokes of the needle and after the core 76 has been raised 70 in readiness for the rotation of the head. Fig. 21 is a similar view showing the head after its rotary movement, and also showing the cooperating parts 101, 110, 114'. As the head 55 and core 76 rotate the string remains 75 in engagement with the slot 53 in the bracket 52, and as the string is wrapped around the core 76 beneath the ridges 102 on the core the restricted extremity of the slot 53 grips one or both parts of the string and thus entirely 80 precludes the possibility of the string being drawn up unevenly through the ring 115. On completion of this rotary movement the member 110 is swung into its operative position (see Fig. 22) so that its forked end 111 en- 85 gages the string and moves same to one side, out of the slot 53 and beneath the ridges 102. This operation of the member 110 is effected by the drum 139 and as the operation con- 90 tinues the further movement of the member 101 causes its forked end 108 to enter the re-cess 104 and as the member 101 enters the said recess the core 76 is lowered by the action of the cam wheel 75 until the opening 100 in the core 76 is in alignment with the recess 104. 95 As the member 101 enters the opening 100 the part 114' engages the inclined face 114 of the sliding gate piece 112 which had been re- 100 taining the loose ends of the string in the vertical bore 56 and as the said gate piece is thus moved aside the loose ends of the string are engaged and pressed by the grooved end 108 of the member 101 and are thus passed be- 105 tween the guide strips or plates 99' and through the opening 100, and are forced be- 110 tween the opposed faces of the spring blocks 106 (see particularly Fig. 17).

The members 101 and 110 are then with- 115 drawn and the cam wheel 75 causes the core 76 to move downward and disengagement of the string from the ridges is positively pre- 120 vented by the strips 99' until the cam or in- clined projection 99 engage the string encir- 125 cling the core 76 and disengages the same from the ridges 102, and during the final por- 130 tion of the downward stroke of the core 76 a pull is exerted on the knot just formed.

The loop or knot raising mechanism shown at 24 to 27 inclusive may or may not be em- 130 ployed according to the particular require- 135 ments, and the disengagement of the string from the ridges 102 by the member 99 com- 140 pletes the cycle of operations unless the said mechanism is employed. As the free ends 145 of the string are retained by a friction grip between the spring blocks 106 and as the string is disengaged from the core 76, a pull, by the operator, on the label, tag or other ar- 150 ticle, or on the upper part of the string tight- 155

ens the knot thus formed and withdraws the free ends from the said spring grip.

When it is desired to employ the loop or knot raising mechanism shown at Figs. 24 to 27 inclusive, the rod 127 is raised by the action of its cam 131 immediately after the release of the string from the ridges 102 in the manner above described, and as the rod 127 engages the shoe 126 and thus swings the members 119, 123 from the position shown at Fig. 24 to that shown at Fig. 26, the loop of string around the back of the core is raised toward the opening 38 and toward the label or other article, and as the motion is continued the fork 118 disengages the loop of string from the hook 117 and presses same towards the label or other article so that the knot formed in the string may be brought close up to the article through or around which the string is looped.

Although the drawings and above specification disclose the best mode in which I have contemplated embodying my invention, I desire to be in no way limited to the details of such disclosure, for in the further practical application of my invention many changes in form and construction may be made as circumstances require or experience suggests without departing from the spirit of the invention within the scope of the appended claims, and it will be readily understood the knot forming mechanism may be adapted to give a simple or "hard" knot or may be so arranged that the extreme ends of the string do not pass through the loop so as to produce a bow-knot affording ease of removal or untying.

What I claim is:

1. String knotting apparatus of the character described, comprising a member for carrying the string to knotting position, means for cutting the string, means for holding the two ends of the cut off string independently of each other, means for manipulating the string to form a loop therein, and means for pushing part of the string through said loop.

2. String knotting apparatus of the character described, comprising a string carrying member, means for reciprocating said member to place the string in position, means for cutting the string to form two free ends, means for holding said free ends independently of each other and means for knotting the string to attach the two free ends thereof comprising a device for pushing a part of the string through a loop formed by another part of the string.

3. String knotting apparatus of the character described, comprising a needle, means for reciprocating the needle to supply the string, means for cutting the string to form two depending free ends, independent means for temporarily clamping each of said free ends, and means for forming a knot in the

string above said ends comprising a device for pushing a part of the string through a loop formed by another part of the string.

4. String knotting apparatus of the character described, comprising a needle for supplying the string, means for manipulating the string to provide two free ends, a core member, means for wrapping the string around said core to form a loop, and means reciprocating at right angles to the core for inserting the free ends of the string through said loop to form the knot.

5. String knotting apparatus of the character described, comprising a rotary head, means for passing the string through said head to provide two free ends, a core member, means for rotating the head to wrap the string around said core member to form a loop, and means for inserting the ends of the string through said core member to form a knot.

6. String attaching apparatus of the character described, comprising a needle for threading the string through an article, means for retaining and cutting the string, and means comprising a rotary head, a reciprocating core mounted centrally in the head, and an eccentric bore in the said head for the passage of the needle, for manipulating the string to form a knot therein.

7. String attaching apparatus of the character described, comprising a string carrying needle, means for reciprocating the needle to penetrate an article, means for cutting the string to form two free ends, and means comprising a rotary head, a reciprocating core mounted centrally in the head, and an eccentric bore in the said head for the passage of the needle, for knotting the string between the said free ends and the said article.

8. String attaching apparatus of the character described, comprising a needle, means for reciprocating the needle to supply the string, means for cutting the string to form two depending free ends, means for temporarily clamping said free ends, and means comprising a rotary head, a reciprocating core mounted centrally in the head, and an eccentric bore in the said head for the passage of the needle, for forming a knot in the string above said ends.

9. String attaching apparatus of the character described, comprising a needle for supplying the string, means for manipulating the string to provide two free depending ends, a core member, an opening in the core, means for wrapping the string around said core to form a loop, and means for inserting the free ends of the string through said opening to form the knot.

10. String attaching apparatus of the character described, comprising a rotary head, means for passing the string eccentrically through said head to provide two free ends, a core member, an opening therein, means

for rotating the head to wrap the string around said member to form a loop, and means moving at approximately right angles to the axis of the head for inserting the 5 ends of the string through said loop to form a knot.

11. String attaching apparatus of the character described, comprising a vertical rotary head, a string supplying needle, means for reciprocating the needle eccentrically through said head to provide two free ends, means for rotating the head to form a loop in the string, and means for inserting the free ends of the string horizontally through said loop 10 to form a knot.

12. String attaching apparatus of the character described, comprising a rotary head, a reciprocating needle for supplying a string eccentrically to the head, means for cutting the string to provide two free ends, a core member concentrically mounted in the head, means for rotating the head to wrap the string around said core member to form a loop, and means for introducing the ends of the string 20 through said core and loop to form a knot.

13. String attaching apparatus of the character described, comprising a rotary head, a string supplying needle, means for reciprocating the needle to feed the string eccentrically through said head, means for cutting the string to provide two free ends, means for temporarily clamping said free ends independently of each other, means for rotating the head to loop the string, and means for introducing the ends of the string 30 through said loop to form a knot.

14. String attaching apparatus of the character described, comprising a rotary head, a needle for feeding a string to said head, means for temporarily clamping the ends of the string, a core in said head, an opening in the core, means for rotating the head to loop the string around said core, means for moving the ends of the string to penetrate said opening and said loop to form a knot, and means for temporarily retaining the said ends to 40 permit tightening of the knot.

15. String attaching apparatus of the character described, comprising a reciprocating needle for supplying the string, means for cutting and retaining the string, a core member, an opening in the core member, means for wrapping the string around said core to form a loop, reciprocating means for moving 50 a part of the string through said loop and through said opening to form a knot, and means whereby the knot is tightened.

16. String attaching apparatus of the character described, comprising a rotary head, a reciprocating needle for supplying two lengths of string to the head, means for cutting the string to provide two free ends, a core member, an opening in the core member, means for rotating the head to wrap the 60 string around said core member to form a

loop, and means for introducing the two ends of the string through said opening and said loop to form a knot.

17. String attaching apparatus of the character described, comprising a rotary head, 70 an eccentric bore in said head, a string supplying needle, means for reciprocating the needle to feed the string twice through said bore, means for cutting the string to provide two free ends, means for temporarily clamping said free ends independently of each other, means for rotating the head to loop the string, and means for pushing the ends of the string through said loop to form a knot. 75

18. String attaching apparatus of the character described, comprising a rotary head, a needle for feeding a string to said head, means for temporarily clamping two ends of the string, a core mounted centrally in said head, means for rotating the head to loop the string 80 around said core, means for moving the two ends of the string in a direction substantially perpendicular to the axis of the head to penetrate said loop and form a knot, and means for temporarily retaining the said ends to 85 permit tightening of the knot.

19. String attaching apparatus of the character described, comprising a reciprocating needle for supplying two lengths of string, means for cutting and retaining the string to 90 form one piece with two depending ends, a rotary core member, means for wrapping the string around said core member to form a double loop, reciprocating means moving at right angles to the axis of said core for 100 moving parts of the string through said loop to form a knot, and means whereby the knot is tightened.

20. String attaching apparatus of the character described, comprising means for supplying the string to an article, means for cutting the string to form two free ends, means for temporarily clamping said free ends, means for manipulating the string between the article and said ends to form a 105 loop, means for introducing the ends of the string through said loop, and spring jaws for gripping the ends of the string after introduction through said loop. 110

21. String attaching apparatus of the character described, comprising a reciprocating needle for passing the string through an article, a hook device for separating the string from the side of the needle, a retaining device for engaging the string, a knife for severing 120 the end of the string, and means for forming a knot in the string comprising a rotary head, a reciprocating core mounted centrally in the head, and an eccentric bore in the said head for the passage of the needle. 125

22. String attaching apparatus of the character described, comprising means for feeding a string to an article, means for cutting the string to provide two free ends, means for temporarily holding said free ends, a rotary 130

head between said ends and the article, means for rotating the head to form a loop in the string, means for pushing the ends of the string through said loop in a direction substantially perpendicular to the axis of the head, and means for changing the plane of the loop to permit said introduction.

23. String attaching apparatus of the character described, comprising reciprocating means for supplying the string, means for manipulating the string to form two free ends, a reciprocating core, means for wrapping the string around the core to form a loop, means for pushing the ends of the string through said loop in a direction substantially perpendicular to the direction of movement of said reciprocating means, and means for depressing one side of said loop to permit said introduction.

24. String attaching apparatus of the character described, comprising means for supplying the string to an article, means for cutting the string to form two free ends, means for temporarily clamping said free ends independently of each other, means for manipulating the string between the article and said ends to form a loop, means for introducing the ends of the string through said loop, spring jaws for gripping the ends of the string after introduction through said loop, and means for tightening the knot thus formed.

25. String attaching apparatus of the character described, comprising a reciprocating needle for passing the string through an article, a hook device for separating the string from the side of the needle, a retaining device for engaging the string, a knife for severing the string to provide two free ends, and means for forming a knot in the string between said ends and the article comprising a rotary head, a reciprocating core mounted centrally in the head, and an eccentric bore in the said head for the passage of the needle.

26. String attaching apparatus of the character described, comprising means for feeding two lengths of string to an article, means for cutting the string to provide two free ends, means for temporarily holding said free ends independently of each other, a rotary head between said ends and the article, a core in said head, a central opening in the core, means for rotating the head to form a loop in the string, means for introducing the ends of the string through said opening and said loop, and means for changing the plane of the loop to permit said introduction.

27. String attaching apparatus of the character described, comprising reciprocating means for supplying the string, means for cutting and manipulating the string to form two free ends, a reciprocating core, an opening in said core, a rotary member for wrapping the string around the core to form a loop, means for introducing the ends of the string

through said loop and said opening, and means for depressing one side of the loop to permit said introduction.

28. String attaching apparatus of the character described, comprising means for supplying the string, means for cutting and temporarily clamping the string, means for looping the string, means for imparting sidewise movement to the string adjacent to said loop, and forked means for pushing the ends of the string through said loop to form a knot.

29. String attaching apparatus of the character described, comprising means for supplying the string, means for cutting the string, means for clamping the cut ends of the string independently of each other, a core member, means for looping the string about said core member, means for imparting sidewise movement to the string adjacent said core member, and a forked reciprocating device for pushing the ends of the string through said loop to form a knot.

30. String attaching apparatus of the character described, comprising means for supplying the string, means for cutting the string, means for temporarily clamping the ends of the string, a core member, means for wrapping the string around said core member to form a loop, a swinging member for imparting sidewise movement to the string adjacent said loop, means for reciprocating the core member to change the position of one side of the loop, and a forked member for pushing the ends of the string through such loop to form a knot.

31. String attaching apparatus of the character described, comprising means for supplying the string, a rotary head for receiving the string, means for rotating said head to form a loop in the string, means for introducing the end of the string through said loop, and spring jaws in the head for engaging the end of the string to facilitate tightening of the knot.

32. String attaching apparatus of the character described, comprising means for supplying two lengths of string, means for cutting and temporarily clamping the string, means for looping the two lengths of string, means for imparting side-wise movement to the string adjacent said loop, and a forked reciprocating member for pushing the ends of the string through said loop to form a knot.

33. String attaching apparatus of the character described, comprising means for supplying the string, means for cutting the string, means for clamping the cut ends of the string, a core member, a rotary head for looping the string about said core member, means for imparting sidewise movement to the string adjacent said core member, and a forked reciprocating device for pushing the ends of the string through said loop to form a knot.

45. String attaching apparatus of the character described, comprising a reciprocating needle for feeding the string through the article, a rotary head, an eccentric bore therein for receiving the string, means for operating the said head to loop the string, means for pushing part of the string through said loop, a hook member engaging said loop, means for operating the hook member to slide the knot towards the article, and means for disengaging the loop from said hook member.

46. String attaching apparatus of the character described, comprising a reciprocating needle for feeding the string, a loop-forming rotary head, an eccentric bore therein for receiving the string, and a knot sliding device comprising a loop-engaging hook mounted on said rotary head, means for swinging the hook in an upward direction, and a fork member for disengaging the hook from the string and for pressing the knot upwardly.

47. String attaching apparatus of the character described, comprising means for feeding the string through an article, a rotary head, an eccentric bore therein for receiving the string, means for cutting and temporarily retaining the string beneath said head, a reciprocating core, means for rotating the head to wrap the string around said core to form a loop, means for frictionally retarding the string during such rotation, means for reciprocating the core to change the plane of the loop, and a reciprocating member adapted to penetrate the loop to introduce part of the string and thus form the knot.

48. String attaching apparatus of the character described, comprising a reciprocating needle for feeding the string through the article, a rotary head, an eccentric bore therein for receiving the string, means for operating the said head to loop the string, means for pushing the ends of the string through said loop, a hook member engaging said loop, means for swinging said hook member to slide the knot upwards towards the article, and a swinging fork for disengaging the loop from said hook member after the raising of the loop.

49. String attaching apparatus of the character described, comprising a table for receiving an article, a vertically reciprocating needle mounted above the table, means for reciprocating the needle to feed the string through the article and through the table, and knot-forming means located beneath the table to receive the string and form a knot therein comprising a rotary head, a reciprocating core mounted centrally in the head, and an eccentric bore in the said head for the passage of the needle.

50. String attaching apparatus of the character described, comprising a flat article-receiving table, a vertically reciprocating needle for feeding the string through the article and through the table, mechanism located

beneath the table for reciprocating the needle and means for receiving and knotting the string comprising a rotary head, a reciprocating core mounted centrally in the head, and an eccentric bore in the said head for the passage of the needle.

51. String attaching apparatus of the character described, comprising an article-receiving table, a control member adjacent thereto, a reciprocating needle above said table, means for operating the needle to thread the string through the article and through the table, means located beneath the table for cutting the string to form two free ends, and means for knotting the string beneath the table comprising a rotary head, a reciprocating core mounted centrally in the head, and an eccentric bore in the said head for the passage of the needle.

52. String attaching apparatus of the character described, comprising a table for receiving an article, a reciprocating needle for feeding the string through the article and through the table, means for reciprocating the needle from beneath the table, means for receiving the string beneath the table and forming two free depending ends, means for temporarily retaining said ends, means for looping the string, means for passing a part of the string through said loop and means for sliding the knot towards the article upon the table.

53. String attaching apparatus of the character described, comprising a table for receiving an article, a vertically reciprocating member mounted above the table, cam means for reciprocating the said member to feed the string through the article and through the table, means for cutting off a portion of string, and knot-forming means located beneath the table to receive the string and to form the knot in said string portion after it has been cut off.

54. String attaching apparatus of the character described, comprising a flat article-receiving table, string supply means above the table, a vertically reciprocating needle for feeding the string through the article and through the table, string cutting means beneath the table, mechanism located beneath the table for reciprocating the needle and means for receiving and knotting the string comprising a rotary head, a reciprocating core mounted centrally in the head, and an eccentric bore in the said head for the passage of the needle.

55. String attaching apparatus of the character described, comprising an article-receiving table, a control member adjacent thereto, a reciprocating needle normally located above said table, means for operating the needle to thread the string through the article and through the table, means located beneath the table for cutting the string to form two free ends, means for temporarily

clamping said ends independently of each other, and means for knotting the string beneath the table.

56. String attaching apparatus of the character described, comprising a table for receiving an article, a needle for feeding the string through the article and through the table, cam means for reciprocating the needle from beneath the table, a rotary head for receiving the string beneath the table, means for cutting the string to form two free depending ends, means for temporarily retaining said ends, means for looping the string, and means for passing the free ends through said loop to form the knot.

57. String attaching apparatus of the character described, comprising a table for receiving an article, a string feeding needle mounted above and extending through the table, means located beneath the table for reciprocating the needle, cutting, clamping and looping the string, and forming and tightening a knot, and drive means therefor.

58. String attaching apparatus of the character described, comprising a table for receiving an article, a vertically reciprocating needle for feeding the string to penetrate the article and form two free ends depending through the table, means for temporarily clamping said free ends, a rotary member for looping the string, means for introducing the ends of the string through said loop to form the knot, and means for manually controlling the operation of the apparatus.

59. String attaching apparatus of the character described, comprising a table for receiving an article, means for feeding the string through the article and through the table, means located beneath the table for cutting the string, means for knotting the string beneath the article, means adjacent to the article receiving table for starting the operation, and means for automatically halting the operation at the end of each cycle of operations.

60. String attaching apparatus of the character described, comprising means for feeding the string through an article, means for receiving, looping and knotting the string beneath the article, a main shaft for driving the apparatus, a clutch device on the main shaft, and means for manually engaging and automatically disengaging the clutch.

61. String attaching apparatus of the character described, comprising means for manipulating the string to engage the article and form two free ends, means for knotting the string, a continuously rotating member for driving the apparatus, a manually engaged clutch device for commencing the operation, a second clutch device for stopping the operation and trip mechanism for

engaging the second clutch after the completion of the cycle of operations.

62. String attaching apparatus of the character described, comprising a flat table for receiving and supporting an article, string supply means above the table, means for feeding the string through the article and through the table, means located beneath the table for cutting the string, a rotary head and reciprocating core for knotting the string beneath the article, and means adjacent to the table for starting the operation.

63. A knot tying machine of the character described comprising a string-carrying needle, reciprocating means for imparting to the needle a four-stroke cycle, means for retaining the free end of the string after the first stroke of the cycle, independent string retaining means for engaging another part of the string after the third stroke of the cycle, means for cutting the string after said third stroke and means for manipulating the string to form a knot therein after the completion of the fourth stroke of the cycle.

64. A knot tying machine of the character described comprising a reciprocating string-carrying needle, means for operating the needle through a four-stroke cycle, means for retaining and cutting the ends of the string to form a loop with two free depending ends after the completion of the fourth stroke of the cycle, means for forming a knot in the said loop and means for tightening said knot.

65. A knot tying machine of the character described comprising a string-carrying needle, means for imparting to the needle a four-stroke cycle, means for separating the string from the needle and for temporarily clamping the same after the first and after the third stroke of each cycle, means for manipulating the string to form a bow-knot, and means for tightening the said knot.

66. Apparatus of the character described for the attachment of string to an article, comprising a needle for penetrating the article, means for imparting to the needle a four-stroke cycle—the needle being caused to penetrate the article during at least one of the strokes of said cycle,—means for cutting the string and for temporarily retaining the free ends thereof and means for knotting the string between the article and said ends.

67. Apparatus of the character described for the attachment of string to an article, comprising a string-carrying needle, means for imparting a four-stroke cycle to the needle,—the needle penetrating the said article during the first and third strokes of said cycle,—means for cutting the string and retaining the free ends thereof, means for knotting the string, and means for moving the knot into close engagement with the said article.

68. A knot tying machine of the character

described comprising a string-carrying needle, reciprocating means for imparting to the needle a four-stroke cycle, means for cutting the string after the third stroke of the needle and means for manipulating the string to form a bow-knot therein after the completion of the fourth stroke of the cycle.

In testimony whereof I have signed my name to this specification.
